UNITED STATES PATENT OFFICE.

WILLIAM M. MEEK, OF SEATTLE, WASHINGTON, ASSIGNOR OF ONE-HALF TO IMOGEN M. LAMBERTON, OF MOUNTAIN HOME, IDAHO.

WRENCH.

No. 916,468.

Specification of Letters Patent. Patented March 30, 1909.

Application filed March 4, 1908. Serial No. 419,186.

To all whom it may concern:

Be it known that I, WILLIAM M. MEEK, a citizen of the United States, residing at Seattle, in the county of King, State of Washington, have invented certain new and useful Improvements in Wrenches; and I do hereby declare the following to be a full, clear, and exact description of the invention, such as will enable others skilled in the art to 10 which it appertains to make and use the same.

My invention relates to wrenches, and more particularly to quick acting monkey wrenches.

15 The object of the invention is to provide a device of this character which will be quick and positive in action, cheap to manufacture, and which will enable the operator to adjust the wrench to any desired size of nut, within 20 the scope of the jaws, in a very rapid manner, without having to operate the adjusting nut.

25 A further object of the invention is the provision of means which enables the operator to positively move the jam or adjusting nut away from its rack in a straight line and to effect this movement with the thumb of the hand which is used in applying the wrench.

30 Heretofore, in wrenches of this type, the lower jaw has been rocked on the shank of the wrench, or the adjusting nut has been pivoted to move at an angle to the shank. With such a construction the adjusting nut has very little movement adjacent its pivotal point and very frequently the threads on the 35 nut at such point will not disengage from their rack connection.

It is the object of my invention to obviate such difficulties, and broadly speaking consists in so mounting the adjusting nut that it 40 moves in a plane substantially parallel to the shank and thereby frees all of its threads from the rack simultaneously.

45 In the drawing which forms a part of this application, Figure 1 is a side elevation of the wrench, Fig. 2 is a similar view with one side of the lower jaw frame in section. Fig. 3 is a detail perspective view of the adjusting nut frame, removed from the wrench, with the adjusting nut journaled therein, and, Fig. 4. 50 is a sectional view showing the nut pressed away from the rack teeth.

Referring more especially to the drawings 1 represents a shank, preferably rectangular in cross section, one end of which serves as an

operating handle while at its opposite end 55 it is provided with a transversely extending upper jaw 2. Extending along the front face of the shank and projecting therefrom are a series of diagonally arranged teeth 3 forming a rack, which will be spoken of hereinafter. The lower jaw 5, which is bored in the usual manner to permit its disposition upon the shank, is provided with a transverse rectangular passage 6 which opens through the rear wall of said jaw and is intersected at 60 right angles by the above-mentioned bore. Within said passage there is disposed a hollow rectangular frame 7 which carries at its forward end a peripherally threaded rotatable nut 8 whose opposite ends are journaled in the top and bottom plates of said frame, the side plates of which latter as well as the side walls of the lower jaw are cut away at 65 such point so as to expose the nut and permit access thereto. This nut has its threads held 70 normally in engagement with the rack teeth 3 by means of a leaf spring 9 which is located within the passage 6 and is secured centrally to the inner face of the front wall of the sliding jaw, the opposite ends of said spring bearing 75 against the front plate of said frame, the top and bottom plates of which are provided with slots 10 through which the shank extends, the length of said slots being slightly greater than the thickness of the shank, 80 to permit a sliding movement of the frame, transversely of the latter, under the tension of the spring. The length of the sliding frame is such that its rear end projects 85 through the open rear wall of the jaw 5 when the nut and rack are in engagement, such end forming an operating portion by means of which the frame may be moved inwardly 90 against the action of the spring, to disengage the nut from the rack when the position of the sliding jaw is to be adjusted, the side walls of said jaw being cut away or concaved at their rear edges, to afford further access 95 to the frame end.

In operation, the thumb of the hand which 100 applies the wrench presses upon the projecting end of the frame and forces the latter inwardly against the tension of the spring 9. This carries the nut 8 out of engagement with the rack teeth 3, whereupon the lower jaw 105 can then be moved as desired. If the adjustment is not fine enough the nut may be rotated to move the jaw gradually on the

rack teeth. It will be seen that the adjusting nut always moves in a plane parallel to the shank and thereby frees all of its threads simultaneously the spring returning the nut and frame to normal positions as soon as the pressure is released.

5 What is claimed is:—

10 A wrench comprising a shank provided with a toothed side and a relatively fixed jaw on one end, a relatively movable jaw 15 slidably mounted on the shank and having a transverse opening therethrough on the toothed side of said shank and a passage intermediate its length perpendicular to said transverse opening and extending through the side of the movable jaw opposite said opening, a hollow block slidable within said

20 passage and having a slot therethrough for the passage of said shank and extending beyond the teeth of the same, a peripherally threaded rotatable nut mounted to turn in said block and engage the teeth of the shank, and a spring located within said opening between the front wall thereof and the inner 25 end of said block, said spring tending to hold the outer end of said block beyond the plane of the movable jaw and said nut in engagement with the shank teeth.

25 In testimony whereof, I affix my signature, 30 in presence of two witnesses.

WILLIAM M. MEEK.
